UNITED STATES PATENT OFFICE.

MORRIS GOLDBERGER, OF CHICAGO, ILLINOIS, ASSIGNOR TO CRESO CREAMERY SUPPLY CO., OF CHICAGO, ILLINOIS, A CORPORATION OF ILLINOIS.

MOTOR-DRIVEN PASTEURIZER.

Application filed October 2, 1922. Serial No. 591,710.

To all whom it may concern:

Be it known that I, MORRIS GOLDBERGER, a citizen of the United States, and a resident of Chicago, in the county of Cook and State 5 of Illinois, have invented certain new and useful Improvements in Motor-Driven Pasteurizers; and I do hereby declare that the following is a full, clear, and exact description thereof, reference being had to the accompanying drawings, and to the characters of reference marked thereon, which form a part of this specification.

This invention relates to improvements in apparatus for treating milk for pasteurizing the same under the well known batch process of pasteurizing, or for otherwise conditioning milk and other liquids.

The invention is herein shown as adapted to the type of apparatus disclosed in my 20 United States Letters Patent, Number 1,438,594, dated December 12th, 1922, and relates in part to means for quickly converting a motor driven pasteurizing apparatus to an overhead shaft and belt-driven apparatus, and in part to special means in a motor driven apparatus for supporting, from the vessel or receptacle, the motor and the speed reducing transmission mechanism between the motor and agitator.

30 Other objects of the invention are to produce a structure of this character which simplifies the installation of a pasteurizing apparatus in the space in a dairy reserved therefor, to means for minimizing the transmission of vibration of the driving motor to the receptacle or vessel and to means for adapting the transmission to drive other apparatus used in association with pasteurizing apparatus.

40 The invention consists in elements, and combination of elements, shown in the drawings and described in the specification, and is pointed out in the appended claims.

As shown in the drawings:

45 Figure 1 is a side elevation of a pasteurizing apparatus embodying my invention.

Figure 2 is a vertical section on line 2—2 of Figure 3.

50 Figure 3 is a partial section and partial elevation, the section being indicated on the line 3—3 in Figure 2.

As shown in the drawings, 10 designates the pasteurizing receptacle supported on suitable legs 11 and provided centrally with 55 an outlet 12 which, as shown, is connected

by a pipe 14 with a pump 15 by which the contents of the receptacle are lifted to a place of disposal of the liquid.

16 designates the upper end of the shaft of the agitator, shown in my aforesaid application, said agitator shaft being rotatably mounted in a vertical bearing 17 that is fixed to a beam 18 which extends diametrically across the top side of the pasteurizing receptacle and may be attached to the wall of the receptacle in the manner shown in my aforesaid application. 19 designates a pulley fixed to the shaft 16. About this pulley is trained a driving belt 20, which belt is also trained about a driving pulley 21, which is fixed to a short upright shaft 22 that is rotatably mounted in an upright bearing sleeve 23, which is made integral with the upper wall of a gear box 24 that is supported at or about the level of the beam 18 of the receptacle 10.

As shown in my prior application, the transmission gear enclosed in the gear box is adapted for driving connection from a shaft. In the present construction, the said shaft 22 is also adapted for driving connection from a motor 25, preferably an electric motor, which is supported at one side of the receptacle and below the top thereof. The means for supporting said motor on the receptacle and for connecting its armature shaft to the upright shaft 22 of the driving transmission are made as follows:

26 designates a bracket comprising a horizontal member 27 that lies upon and is bolted or otherwise fixed to the beam 18, a vertical member 28 and a connecting web 29, shaped to give general triangular formation to the said bracket. 30 designates an upright plate which lies with its side face at its upper end face against the outer face of the bracket member 28 and is attached thereto by the same bolts 31 which fix the gear box 24 rigidly in place in a manner to be supported on the beam 18. As shown 90 said bolts extend loosely through openings in the upright member 28 of the bracket and the plate 30, and are threaded into registering openings in the adjacent side wall 32 of the gear box. The motor 25 is fixed to said plate 30 in the manner of a wall mounting, the frame of the motor being provided with a bracket 33 through which fastening bolts 34 extend to hold it in place. 100 Bolted to, or otherwise attached to said 105

plate 30 near the lower end thereof is a bearing 35 in which is rotatably mounted a horizontal shaft 36. Fixed to one end of said shaft 36 is a pulley 37 that is connected by a belt 38 to a pulley 39 on the armature shaft of the motor 25. Fixed to the other end of the shaft 36 is a smaller pulley 40 that is connected by a belt 41 with a larger pulley 42. The latter pulley is pinned 10 upon or otherwise secured to a horizontal shaft 43 which is rotatably mounted in suitable bearings 44, 44 supported by the side walls of the gear box. Fixed to said shaft 43, within the gear box, is a beveled pinion 15 45 which meshes with a beveled gear 46 fixed to the lower end of the shaft 22.

With this construction, it will be noted that the ratios of the motor pulley 39 to the transmission pulleys 37, 40, 42, 21 and 19, 20 and the ratios of the gears 45, 46 are such as to suitably reduce the high speed of an ordinary commercial motor to a relatively slow speed delivered to the agitator shaft through the belt 20; it being understood 25 that the agitator shaft will be operated at a slow speed during the pasteurizing operation.

One of the features of the present invention resides in mounting the motor 25 well 30 up towards the level of the beam 18 which carries the agitator shaft and the motor supporting plate 30, as well as the gear box and the transmission associated therewith, and in locating a portion of the speed reducing transmission towards the lower end of said plate 30. This arrangement has the effect, so to speak, of decreasing the lever arm of the motor with respect to the mechanism which it drives, and also provides a 35 very convenient and compact means of arranging the speed reducing mechanism between the motor and the driving agitator shaft 19. Therefore, transmission of vibration to the receptacle, due to the high speed 40 of the motor, is greatly minimized.

It is desirable, because of sanitary rules and regulations, that a space shall intervene 50 between the motor mounting plate 30 and the side wall of the pasteurizing receptacle. For this purpose the bracket 26 can be extended slightly beyond the plane of the vertical side of the receptacle, as shown in Figure 2, to space the upper end of the motor mounting plate from the receptacle wall; and the lower end of said plate may be 55 spaced from said wall by a set screw 47 threaded through said plate and bearing at its end against the outer face of said receptacle wall.

It will be observed that by interposing 60 the motor mounting plate between the upright flange or member 28 of the bracket 26 and the adjacent side wall of the gear box, said plate can be very rigidly connected to 65 the load carrying element of the apparatus,

to-wit: the beam 18, and it will be furthermore observed that said construction provides a very compact and rigid means of joining the gear box to said plate and to the angle bracket of said beam. 70

The construction described enables the pasteurizing apparatus to be installed at the most convenient place in a dairy and without reference to overhead driving shafts. At the same time the construction is such 75 that, with the use of shorter screw bolts 31 the gear box can be attached directly to the upstanding member of the angular bracket 26 so as to arrange the transmission gear for connection to a driving shaft when so desired, in which event the motor and its mounting plate are omitted and driving power can be transmitted by belt to the shaft 43. 80

Preferably the said motor and a portion of the transmission mechanism is enclosed by a hood 48 which can be removably attached to the motor mounting plate in any suitable manner.

By extending the shaft 43 laterally from the gear box 24, it may be made to receive 90 a pulley 49 by which to drive, through a suitable belt 50, the pump 15 or other auxiliary device useful about the pasteurizing device, such as a milkforce pump, a brine pump, etc. 95

I claim:

1. The combination with a receptacle, a beam supported across and fixed to the top thereof, and an agitator shaft mounted in a bearing supported on said beam, of a 100 vertical motor mounting plate arranged at one side of the receptacle and fixed thereto, a gear box supported from the beam, a motor mounted on said plate below said box, and a reducing driving transmission supported partly on said plate below said box and partly in the gear box for transmitting driving power from the motor to said agitator shaft.

2. The combination with a receptacle, a beam extending diametrically across the top thereof and fastened thereto, an agitator shaft mounted in a bearing supported on said beam, and a motor at the side of said receptacle, operatively connected through speed reducing transmission with and driving said agitator shaft, of a supporting plate for said motor and a portion of said speed reducing transmission, a gear box enclosing and supporting another portion of said speed reducing transmission and means for connecting and supporting the upper end of said motor supporting plate and the gear box to said beam, said plate depending free ended from its connection and support. 115 120 125

3. The combination with a receptacle, a beam extending diametrically across the top thereof and fastened thereto, an agitator shaft mounted in a bearing supported on said beam, and a motor at the side of said 130

- receptacle, operatively connected through speed reducing transmission with and driving said agitator shaft, of a vertical motor mounting plate at one side of said receptacle, said motor and a portion of said speed reducing transmission being supported on said plate, a gear box outwardly beyond said beam enclosing another portion of said speed reducing transmission and means to support said plate and said box on one end of said beam.
4. The combination with a receptacle, a beam extending diametrically across the top thereof and fastened thereto, an agitator shaft mounted in a bearing supported on said beam, a motor at the side of said receptacle, and a gear box including a shaft having driving connection with said agitator shaft, of a vertically arranged plate at the side of the receptacle and extending upwardly therebeyond to support said motor, a bracket fixed to said beam, said plate being between said bracket and gear box, means common to said plate and gear box for fixing them to and supporting them on said bracket, and a speed reducing transmission supported on said plate and gear box for transmitting driving power from said motor to said agitator shaft.
5. The combination with a receptacle, a beam extending diametrically across the top thereof and fastened thereto, an agitator shaft mounted in a bearing supported on said beam, a motor at the side of said receptacle, and a gear box including a shaft having driving connection with said agitator shaft, of a vertically arranged plate at the side of the receptacle to support said motor, a bracket fixed to said beam, said plate being interposed at its upper end between said bracket and gear box, means for fixing said plate and gear box to said bracket and constituting the support for said plate, and a speed reducing transmission supported on said plate and gear box for transmitting driving power from said motor to said agitator shaft.
6. The combination with a receptacle, a beam extending diametrically across the top thereof and fastened thereto, an agitator shaft mounted in a bearing supported on said beam, a motor at the side of said receptacle, and a gear box including a shaft having driving connection with said agitator shaft, of a vertically arranged plate at the side of the receptacle to support said motor, a bracket fixed to said beam, said plate being between said bracket and gear box, means for fixing said box and plate to said bracket, a speed reducing transmission supported on said plate and gear box for transmitting driving power from said motor to said agitator shaft, and an adjustable bear-
- ing element at the lower end of said plate for contact with the side of said receptacle.
7. The combination with an agitator bearing supporting beam of a receptacle, a bracket fixed to one end of said beam, a gear box, a motor supporting plate insertible between said gear box and bracket, means piercing said bracket, said plate and gear box for removably and interchangeably supporting the gear box and said plate on said beam, a motor mounted on said plate, and a speed reducing transmission operatively connected to said motor and supported on said plate and gear box.
8. The combination with a horizontal beam adapted to extend across and to be fixed at its ends to a receptacle top and a vertical shaft rotatively supported on said beam, of a motor mounting plate and a gear box supported on one end of said beam, said gear box projecting beyond said beam, and said plate depending free ended from said beam and the gear box, a motor mounted on said plate below and adjacent to the plane of said beam and speed reducing gears connecting said motor to said shaft, supported partly on said plate below said motor and partly in said gear box.
9. The combination with a horizontal beam provided at one end with a mounting bracket, of a motor mounting plate and a gear box, said gear box projecting beyond said beam, and said plate depending free ended from said beam and box and removably fixed at its upper end between said gear box and bracket whereby, upon removal of said plate, said gear box can be connected to and supported on said bracket, a motor mounted on said plate below and adjacent to the plane of said beam and speed reducing driving mechanism operatively connected to and driven by said motor and supported partly on said plate and partly in said gear box.
10. The combination with a horizontal beam adapted to extend across and to be fixed to the top of a receptacle, of a motor mounting plate supported on one end of said beam and depending therefrom, a gear box supported on said beam and overhanging said plate, a motor wall-mounted on said plate below and adjacent to said box, a transverse rotative shaft supported on the lower end of said plate, speed reducing driving means connecting said shaft to said motor, a second rotative shaft rotatively supported in said box and parallel to the first mentioned shaft, and speed reducing driving means connecting said shafts.

In witness whereof I claim the foregoing as my invention, I hereunto append my signature this 25th day of September, 1922.

MORRIS GOLDBERGER.
